UNITED STATES PATENT OFFICE.

HARRY H. HANCOCK, OF SWAMPSOCKET, MASSACHUSETTS, ASSIGNOR TO HENRY A. SAWYER, OF LYNN, MASSACHUSETTS.

PRINTER'S QUOIN.

Application filed January 25, 1923. Serial No. 614,743.

To all whom it may concern:

Be it known that I, HARRY H. HANCOCK, a citizen of the United States, residing at Swampscott, in the county of Essex and 5 State of Massachusetts, have invented certain new and useful Improvements in Printers' Quoins, of which the following is a specification.

The present invention relates to an improvement in printers' quoins generally, and more particularly, upon the one shown, described and claimed in my co-pending application, Serial No. 530,569, filed January 20, 1922. An object of the present invention is to produce a quoins which is comparatively thin or narrow, but which may be expanded to a relatively large extent as compared with its narrowness.

Another object of the invention is to provide improved guiding means for the side members of the quoins which will facilitate greater range of expansion of the quoins. Other objects of the invention will appear hereinafter.

These being among the objects of the present invention the same consists of certain features of construction and combinations of parts to be hereinafter described and then claimed with reference to the accompanying drawings illustrating a desirable embodiment of the invention, and in which:—

Fig. 1 is a perspective view of the improved quoins;

Fig. 2 is a top view, partly in section, and parts in dotted lines;

Fig. 3 is a side elevation, partly broken away;

Fig. 4 is a top view, partly broken away, showing the quoins fully expanded; and

Fig. 5 is a transverse section of the quoins when it is contracted.

The metallic side members 10, 11 of the quoins are provided with inclined inner faces 45 12, 12 in their lower portions, the faces converging towards each other. A wedge 13 is adapted to act against the inclined faces for the purpose of expanding the quoins, and it is provided with a screw-threaded opening 14 for receiving the screw-threaded stem 15 of a screw having a head 16. Preferably, the screw-threads are square in cross section, as shown. The head of the screw is provided with a socket 17, preferably square. The head 16 is adapted

to turn upon the side members 10, 11 when a suitable wrench is applied to the socket 17 and adjust the wedge.

One of the side members of the quoins carries a guide-pin 18, preferably of metal tubing, while the other member carries another similar guide-pin 19. The opposite ends of the two guide-pins 19 at opposite sides of the quoins are provided with outward annular shoulders 20, 21, and the other ends of the guide-pins are adapted to be screwed into the side members which carry the pins, as indicated at 22. When the side members 10, 11 are pressed together or contracted, so that the inner faces thereof are 60 in contact, and the wedge is in its lowermost position, the length of each guide-pin 18, 19 is preferably equal to the combined widths of the side members.

As each side member carries a guide-pin 75 at one end, so that there is one such pin at opposite ends of the quoins, that end of the other side member which is opposite one of said guide-pins carries a guide 23 or 24, as the case may be, each of the said guides being preferably composed of similar metal tubing. Guide 23 is provided with an inward annular shoulder 25, the edge of which

fits snugly yet slidably upon the corresponding guide-pin, while the other guide 24 is provided with an inward annular shoulder 26 to fit on and receive its corresponding guide-pin, so that the members of the guiding means at corresponding ends of the side members are adjustable upon each other, 80 or telescoped together. The opposite unshouldered end of one guide preferably has a drive fit with its corresponding side member, while the corresponding end of the other side member is provided with a socket 85

36, into the closed end of which the corresponding guide-pin is preferably screwed, as described, and surrounding such guide-pin said socket forms a recess to receive and telescope with the shouldered end of the said guide when the side members are contracted. There is a similar arrangement for the guide at the other end of the quoins. The length of the guides 23, 24 is somewhat less than the width of the quoins when contracted, and the surfaces which slide on each other should be snugly fitted, but so that there is little friction. With the described guide means at both ends of the quoins, it is clear that the quoins may be ex- 100

105

110

panded considerably relatively to its thickness, that is, the gap which is formed between the side members by the adjustment of the quoin may be increased to considerable varying degrees, for the reason that the guide members of each guiding means are adapted to be nested, as it were, into both of the side members. Considering, therefore, the extent of width to which the 10 quoin may be expanded, the amount of metal used in the side members is reduced to a minimum. In some printers' shops guiding means as described might be all that is desired, but in others, it might be 15 preferred to have the quoin provided with springs which are adapted to automatically contract the quoin whenever the adjusting-screw 15 is screwed into the wedge 13. To this end, in each guiding means the space 20 between the inner wall of the guide and the outer wall of the guide-pin is provided with a helical expansion-spring 27 or 28, each spring having preferably a very few convolutions, and the ends of each spring 25 bear upon the respective shoulders of the guide and guide-pin.

Each guide-pin 18, 19 is preferably provided with a nick or notch 29 for the purpose of enabling a screwdriver to be applied for the purpose of attaching or detaching each guide-pin, and instead of being made tubular, it is obvious that each guide-pin may be solid. A cavity 30 is formed at the midlength of each side member 10, 11, and it is preferably semi-circular so as to conform to the circularity of the head 16 of the adjusting-screw, the two 35 semicircular cavities providing a recess to receive the head of the screw snugly when 40 the side members are drawn together in contact. Preferably, the inclined inner faces 12 of the side members 10, 11 constitute the side walls of recesses cut in the side members, and the ends of which are 45 formed by parallel walls 32, so that the length of each recess is less than the distance between the two guiding means, so that the height to which the wedge received in said recesses may be raised by the 50 adjusting-screw is not restricted by the guiding means, as the wedge in its uppermost position will be located between these two guiding means.

Preferably, means are provided for connecting the adjusting-screw 15 with the wedge 13, so that the two will not become disconnected when the screw is screwed from the wedge as far as desirable. To 55 this end, the threaded portion of adjusting-screw 15 has an internally screw-threaded bore at its lower end, or the end away from the head 16, for the purpose of receiving the screw-threaded stem of a set-screw 33, the head of which is countersunk in a recess 60 34 in the bottom or wider portion of the

wedge, the diameter of the head of set-screw 33 being greater than the diameter of the adjusting-screw, and the edge of the set-screw head forming an abutment and being adapted to come in contact with a shoulder 35. The thread for the set-screw 33 is reverse to the thread for the adjusting-screw of the quoin.

It is obvious that the invention may be variously modified without departing from 75 the spirit and scope thereof as defined in the claims.

What I claim as new is:

1. In a printer's quoin, the combination of side members, projecting guides carried 80 by one of the members, projecting guides carried by the other member and adjustable on aforesaid guides, each of said guides extending within both of the side members, and means for forcing said members apart. 85

2. In a printer's quoin, the combination of side members, projecting guides carried by one of the members, projecting guides carried by the other member and adjustable on aforesaid guides, means for forcing said 90 members apart, and helical springs for drawing the members together.

3. In a printer's quoin, the combination of side members, projecting guide-tubes carried by one of the members, projecting guides carried by the other member and telescoping in said guide-tubes, said tubes and guides being pieces separate from and extending within both side members, and means for forcing said members apart. 95

4. In a printer's quoin, the combination of side members, telescoping pairs of guides carried by and connecting the members, the outer guide of each pair telescoping with one of the side members, and means for 100 forcing said members apart.

5. In a printer's quoin, the combination of side members, telescoping pairs of guides carried by and connecting the members, one of the guides of each pair telescoping with one of the side members, and means for forcing said members apart, and springs arranged within the telescoping guides, and arranged to draw the members together. 110

6. In a printer's quoin, the combination of side members having inclined, converging, inner faces, a wedge bearing on said faces and having a screw-threaded opening, an adjusting-screw engaged in said opening and having a head at one end bearing on said side members, means associated with the threaded opposite end of the screw connecting the wedge and screw and constituting an abutment for the wedge, thereby preventing detachment of the screw or the wedge from the quoin, and guide means for connecting the side members. 115

7. In a printer's quoin, the combination of side members having inclined, converging, inner faces, a wedge bearing on said 120 125 130

faces and having a screw-threaded opening, an adjusting-screw engaged in said opening and having a head bearing on said side members, projecting guides carried by one of the members, and projecting guides carried by the other member and adjustable on aforesaid guides.

8. In a printer's quoin, the combination of side members having inclined, converging, inner faces, a wedge bearing on said

faces and having a screw-threaded opening, an adjusting-screw engaged in said opening and having a head bearing on said side members, projecting guides carried by one of the members, and projecting guides carried by the other member and adjustable on aforesaid guides, and springs acting to draw said members together. ¹⁵

HARRY H. HANCOCK.
